UNITED STATES PATENT OFFICE.

CHARLES REED, OF PORTLAND, INDIANA, ASSIGNOR OF ONE-HALF TO JOHN R. REED, OF SAME PLACE.

HOOP-RACKING MACHINE.

SPECIFICATION forming part of Letters Patent No. 653,528, dated July 10, 1900.

Application filed July 27, 1899. Serial No. 725,263. (No model.)

To all whom it may concern:

Be it known that I, CHARLES REED, of Portland, in the county of Jay and State of Indiana, have invented a new and Improved Hoop-5 Racking Machine, of which the following is a full, clear, and exact description.

My invention relates to an improvement in devices for racking or splitting hoops from a bar, and comprises the novel features here-10 inafter described and claimed.

Reference is to be had to the accompanying drawings, forming a part of this specification, in which similar characters of reference indicate corresponding parts in all the figures.

15 Figure 1 is a side elevation of my device. Fig. 2 is a longitudinal sectional elevation. Fig. 3 is a perspective view showing the end of the bar from which the hoops are made prepared for introduction in the machine. 20 Fig. 4 is a plan view of my device, showing the standard carrying the operating-shaft in section; and Fig. 5 is a sectional elevation taken upon the line 5-5 of Fig. 2.

The object of my invention is to produce 25 a machine which will rapidly split hoops from bars of wood. In making hoops from lumber it is customary to split the lumber into bars which are of a thickness corresponding with the width of the hoop and of such a width as 30 to make a number of hoops. These are then checked at one end and then split up into separate hoops. My machine takes bars which are thus prepared by being checked at the ends and splits them up into hoops by 35 passing the bar through the machine.

The machine is provided with a suitable framework, within which is secured a bed, which consists of two parts B and C, slightly offset from each other. In the upper part 40 are placed two sets of rollers H and h, one of the rollers being connected with a feed mechanism, so as to advance the bar to the breaker-head. At the end of the upper section of the bed is placed a fulcrum-block G, the upper 45 end of which is preferably covered with a corrugated metal plate, as clearly shown in Fig. 2. This fulcrum-block rests upon an eccentric-pin g, which is connected with a lever g'. By operating it the elevation of the fulcrum-block 50 may be slightly varied to adjust the device for use with bars of different thickness. The

set of rollers h which are next to the fulcrum-block are grooved or provided with flanges separated a distance equal to the thickness of the bars which are being used, so that 55 the bar cannot twist or roll while being operated upon.

Just above the fulcrum-block G and at a level corresponding with the level of the lower portion of the upper rollers H and h is 60 a transverse bar I, which is firmly secured to the sides A of the machine-frame. The sides A of the machine-frame are preferably made about six inches apart. The grooves in the rolls h, which receive the bars, are lo- 65 cated in the center of their length. The bars are also guided to these grooves by means of bevel guide-plates b, which are secured in the section B of the bed. Pivoted in the opposite or rear end of the frame A is the breaker- 70 bar D. This is pivoted upon an eccentric-pin d, which also has a crank-arm d' secured thereto, by means of which the breaker may be adjusted toward or from the fulcrum-block G. The swinging or working end of 75 the breaker-bar D reaches to near the fulcrum-block G and is rounded, the rounded working surface being preferably covered with a corrugated metal plate D', as shown in Fig. 2. The corrugations in the plates 80 upon the fulcrum-block and breaker-bar are designed to prevent slipping upon the hoop-bar while being operated upon.

Upon suitable standards A', secured to the frame, is mounted a shaft E above the bed. 85 This shaft has a pulley-wheel E' secured thereto and adapted to receive a belt, by which means it is turned. This shaft has an eccentric e secured thereto and having an eccentric-strap e' about the eccentric and connect- 90 ed with a rod e'', which is pivoted to lugs e'', secured to the swinging end of the breaker D. By this means the breaker is given a vertical reciprocating movement.

The two arms d' and g', by which the breaker 95 and the fulcrum-block are adjusted in position, are connected with a common rod K, which leads to the front of the machine and is connected with a hand-operated lever K', so that both may be adjusted simultaneously. 100 The upper rollers H and h of each set are mounted in frames H' and h', so that they may

be adjusted vertically to accommodate them to bars of different thickness. These frames are mounted to slide vertically in suitable guides upon the machine-frame and are pivotally secured to a lever J, said lever being pivoted at one end to one of the standards A' and at its other end is connected with a rod having weights J' thereon, by which means the rollers H and h are held down in position 10 upon the hoop-bars.

One of the feed-rollers H, being preferably the lower one, is connected with the shaft E in such manner as to give a step-by-step movement to the hoop-bar. At its outer end it is 15 provided with a ratchet-wheel L, which is engaged by a pawl M upon a lever L'. A stop-pawl M' is also provided, which engages the ratchet-wheel to prevent backward movement. The pawl-lever L' is slotted and has a 20 pin N mounted to slide therein and adapted to be connected with an operating-link F². This operating-link is connected to said pin by passing through a hole therein and is secured in place therein by a set-screw entering 25 one side of the pin. The pin N is also secured to a link O, by which it may be readily adjusted to different positions in the lever L'. The link O is connected at one end to a lever P, which is mounted upon the frame A and 30 has a rod E' connected thereto and leading to a hand-operated lever P², located at the forward end of the machine. By this means the throw of the pawl-lever L' may be varied by moving the pin N toward the pivot or to the 35 outer end thereof, as desired.

The link or rod F², by means of which the pawl-lever L' is reciprocated, is connected at one end with an eccentric-strap F', which is mounted upon an eccentric F, secured to the 40 shaft E. In Fig. 2 a hoop-bar R is shown in position.

My device is operated as follows: The hoop-bars are first checked at one end, as shown in Fig. 3. They are then introduced to the machine, the checked end first, said end being 45 passed through the feed and guide rollers H and h. The checked end passes over the fulcrum-block G until it is engaged by the reciprocating breaker D. This end is then bent 50 downwardly, the body of the bar being firmly held by the rollers and the bar I. As the end of the bar is bent downward the lines of weakness started in the bar by the checking are continued by the bending operation, thus extending the splits farther from the end of the 55 bar. The bar is fed forward by short step-by-step movement, and at each forward movement the breaker is brought down, thus bending the bar and continuing the splits therein. 60 By this means the bar is split from end to end.

By placing the bar I, which restrains the upper side of the hoop-bar, close up to the breaker and immediately over the fulcrum-block G the bars may be split very close to 65 the end or entirely out.

Having thus fully described my invention,

I claim as new and desire to secure by Letters Patent—

1. A hoop-racking machine, comprising a hoop-bar-feeding mechanism, a fulcrum-block, means for adjusting the fulcrum-block vertically, a breaker, and means for reciprocating the breaker, substantially as described. 70

2. A hoop-racking machine, comprising a hoop-bar-feeding mechanism, a fulcrum-block, means for adjusting the fulcrum-block vertically, a pivoted breaker, means for swinging the free end and for adjusting the breaker toward and from the fulcrum-block, substantially as described. 75

3. A hoop-racking machine, comprising a breaker and means for moving it vertically to break or rack the hoop-bar, hoop-bar holding and presenting means, and a vertically-adjustable fulcrum-block, substantially as 85 described. 80

4. A hoop-racking machine, comprising a breaker and means for moving it vertically to break or rack the hoop-bar, hoop-bar holding and presenting means, a vertically-adjustable fulcrum-block, and means for shifting the breaker toward or from the fulcrum-block, substantially as described. 90

5. A hoop-racking machine comprising a step-by-step feeding mechanism for the hoop-bar, means for varying the feed of said mechanism, a fulcrum-block, a breaker, and means for actuating the breaker, substantially as 95 described. 95

6. A hoop-racking machine, comprising a hoop-bar-feeding mechanism, means for varying the feed of such mechanism, a fulcrum-block, a breaker pivoted at one end, means connected with the other or working end of said breaker for swinging the same, and means 105 for adjusting the breaker toward and from the fulcrum-block, substantially as described. 100

7. A hoop-racking machine, comprising a breaker having an eccentric pivot-pin whereby it may be adjusted toward and from the fulcrum-block, means for swinging the breaker upon its pivot, a fulcrum-block mounted to move in vertical guides, an eccentric-pin supporting the fulcrum-block whereby it may be adjusted vertically, connections between the 115 said eccentric-pins whereby they may be both turned at once, and hoop-bar presenting and holding mechanisms, substantially as described. 110

8. A hoop-racking machine, comprising a 120 bed formed in two offset portions, a breaker movable vertically over the bed near the point of offset, and means for reciprocating said breaker, substantially as described.

9. A hoop-bar-racking machine, comprising a bed formed in two offset portions, a breaker movable vertically over one portion of the bed near the point of offset, means for reciprocating said breaker, and means for holding and feeding the hoop-bar located beyond the offset from the breaker, substantially as described. 125 130

10. A hoop-racking machine, comprising a bed formed in two offset portions, a breaker movable vertically over one portion of the bed near the point of offset, means for reciprocating said breaker, and a bar for engaging the upper side of the hoop-bar, substantially as described. 65
11. A hoop-racking machine, comprising a bed formed in two offset portions, a breaker movable vertically over the lower portion of the bed near the offset, means for reciprocating the breaker, an adjustable fulcrum-block at the offset end of the upper portion of the bed, and hoop-bar-feeding rollers in the upper portion of the bed, substantially as described. 70
12. A hoop-racking machine, comprising a bed formed in two offset portions, a breaker movable vertically over the lower portion of the bed near the offset, means for reciprocating the breaker, and means for adjusting the breaker toward and from the offset, substantially as described. 75
13. A hoop-racking machine, comprising a bed formed in two offset portions, a breaker movable vertically over the lower portion of the bed near the offset, a shaft having eccentric or crank connection with the breaker to reciprocate it vertically, an adjustable fulcrum-block at the offset end of the upper portion of the bed, hoop-bar-feeding rollers in the upper portion of the bed, a step-by-step feeding means for said rollers, and an eccentric on the shaft connected with said roller-feeding mechanism to operate it, substantially as described. 80
14. A hoop-carrying machine, comprising a bed formed in two offset portions, a breaker movable vertically over the lower portion of the bed near the offset, and for reciprocating the breaker, an adjustable fulcrum-block at the offset end of the upper portion of the bed, hoop-bar-feeding rollers in the upper portion of the bed, and side guides in the bed presenting the bar to the feeding-rollers, substantially as described. 85
15. A hoop-racking machine, comprising a bed formed in two offset portions, a breaker movable vertically over the lower portion of the bed near the offset, means for reciprocating the breaker, an adjustable fulcrum-block at the offset end of the upper portion of the bed, hoop-bar-feeding rollers in the upper portion of the bed, and flanged guide-rollers engaging the bar adjacent the feed-rollers to prevent the bar from rocking or twisting, substantially as described. 90
16. A hoop-racking machine, comprising a bed formed in two offset portions, a breaker movable vertically over one portion of the bed near the point of offset, means for reciprocating said breaker, hoop-bar-feeding mechanisms and flanged guide-rollers engaging the hoop-bar near the offset to prevent rocking or twisting of the bar, substantially as described. 95
17. A hoop-racking machine, comprising a bed formed in two portions offset from each other, a breaker movable vertically over the lower portion of the bed near the offset, feed-rollers in the upper portion of the bed, a shaft having reciprocating connections with said breaker, a ratchet-wheel connected with one of the feed-rollers, an arm having a pawl engaging the ratchet-wheel, a rod having reciprocating connection with the shaft and a slideable connection with the pawl-arm, and a shifting-lever connected with said rod whereby the throw of the pawl-arm may be varied at will, substantially as described. 100
18. A hoop-racking machine, comprising a movable breaker, means for actuating the same, a fulcrum-block over which the hoop-bar passes to the breaker, and a bar located immediately above the fulcrum-block, and between which and the fulcrum-block the hoop-bar passes, substantially as described. 105
19. In a hoop-racking machine, a breaker pivoted at one end on an eccentric pivot whereby it may be adjusted, and a shaft having an eccentric or crank connection with the other end of the breaker to swing the same, substantially as described. 110
20. In a hoop-racking machine, a fulcrum-block, a breaker having an eccentric pivot-pin whereby it may be adjusted toward and from the fulcrum-block, and means for swinging the breaker upon its pivot, substantially as described. 115
21. In a hoop-racking machine, a breaker, means for actuating the same, a step-by-step feeding mechanism for the hoop-bar and an eccentric connected with said feeding mechanism to operate it, substantially as described. 120
22. In a hoop-racking machine, a breaker, a fulcrum-block, adjusting devices for the breaker and fulcrum-block, and a connection between the said adjusting devices whereby they may be actuated simultaneously. 125
23. In a hoop-racking machine, a breaker, means for actuating the same, upper and lower feeding-rollers for the hoop-bar, means connected with one of said rollers for giving a step-by-step movement to the hoop-bar, vertically-adjustable frames in which the upper rollers are mounted, and a lever to which said frames are pivotally secured, the said lever being pivoted at one end and weighted at the other end, substantially as described. 130
